CIRCULAR STEAMING UNIT FOR
UMBRELLAS

Alvin F. Polan, Baltimore, Md.

Application January 13, 1947, Serial No. 721,752

2 Claims. (Cl. 68—6)

1

This invention relates to a means for steaming and thereby shrinking umbrella covers which are mounted on the frames.

An object of this invention is to provide a steam injecting means which is adapted to direct steam against the lower side of an open umbrella so as to thoroughly moisten the cover and shrink the cover on the open frame so that the cover will be tight on the frame.

Another object of this invention is to provide an umbrella steaming device of this kind which includes means for supporting the frame so that the open umbrella will be properly positioned relative to the nozzle structure and can be easily and quickly mounted and removed.

A further object of this invention is to provide a steaming device of this kind which is simple in construction and is designed to evenly distribute the steam beneath and inside the open umbrella.

With the above and other objects in view, my invention consists in the arrangement, combination and details of construction disclosed in the drawings and specification, and then more particularly pointed out in the appended claims.

In the drawings,

Figure 1 is a top plan view of an umbrella steamer constructed according to an embodiment of this invention.

Figure 2 is a sectional view taken substantially on line 2—2 of Figure 1.

Figure 3 is a detail side elevation of the device with the umbrella in section.

Figure 4 is a fragmentary sectional view taken on the line 4—4 of Figure 1.

Figure 5 is a bottom plan view of the device.

Figure 6 is a fragmentary sectional view taken on line 6—6 of Figure 5.

Referring to the drawings, the numeral 10 designates generally a supporting stand which is formed of upright legs 11 connected together at their upper ends by upper top forming bars 12. A transversely extending plate 13 extends between one pair of the top forming bars 12 and forms a support for the umbrella stick holder as will be hereinafter described.

The stand 10 has mounted on the top thereof a steam ejecting head generally designated as 14. The head 14 is formed of a pair of concentric spaced frusto-conical walls 15 and 16, connected together by upper and lower walls 17 and 18 respectively. The wall 15 is the outer wall and is formed with a plurality of steam discharge openings 19. The bottom wall 18 has secured thereto a plurality of circumferentially spaced apart 55 frame.

2

nipples 20 to which are adapted to be connected steam conducting pipes 21, each having a valve 22 interposed therein. The steam ejecting head 14 also has extending downwardly from the bottom wall 18 a drain nipple 23 with which a drain pipe 24 is connected and a drain valve 25 is interposed in the drain pipe 24. In this manner the condensate in the head 14 may be periodically drained therefrom. The stand 10 has extending 10 upwardly from the plate 13 thereof an umbrella holder which includes a tubular member 26 which is open at the upper and lower ends thereof and is formed at its upper end with a funnel shaped umbrella supporting member 27.

15 The stick 28 of the umbrella is adapted to be extended downwardly through the tubular member 26 and the bracing members 29 of the umbrella are adapted to rest on the upper large end of the supporting member 27. The umbrella

20 which is generally designated as 30 is disposed in open position over the head 14, as shown in Figures 2 and 3, with the outer portion or marginal portion of the umbrella cover engaging over the head 14. In this manner the steam which

25 is discharged through the openings or jets 19 will be directed against the outer portion of the umbrella cover and this steam will then move upwardly and inwardly to moisten the inner portion of the cover. In this manner the cover will be moistened to the desired degree for shrinking the cover on the frame so that when the frame is in open position the umbrella cover will be tightly stretched.

30 Whilst I have shown the steaming head 14 as being of frusto-conical configuration, it will be understood that this head may be of angular configuration if desired, and of a size such that the cover of the umbrella will be supported in slight spaced relation to the steam jets which are formed in the steaming head.

35 In the use and operation of this device, the umbrella 30 is disposed in open position with the stick 28 extended downwardly through the tubular member 26 and the braces 29 for the ribs resting on the upper flared end of the funnel-shaped support 27. The valves 22 may then be opened so that steam will be ejected through the jet openings 19 against the under side of the umbrella cover.

40 With a device as hereinbefore described, the umbrella cover will be thoroughly and quickly steamed to provide for the desired shrinking of the cover so that the cover when dry will be tightly disposed on the ribs of the umbrella

I do not mean to confine myself to the exact details of construction herein disclosed but claim all variations falling within the purview of the appended claims.

What I claim is:

1. An umbrella steaming unit comprising a stand, a centrally disposed upwardly opening tubular support carried by said stand adapted to receive the stick of an umbrella, a steam supply main, a steam ejector carried by said stand about said support and connected to said main at circumferentially spaced points, said steam ejector comprising a hollow frusto-conical body having downwardly divergent side walls, said walls formed with upwardly and outwardly opening steam discharge openings for discharging steam against the under side of the umbrella, and a funnel shaped member carried by said support with which the rib braces of the umbrella are engageable for supporting the open umbrella on said unit.

2. An umbrella steaming device comprising a frusto-conical steam ejector, spaced inner and

outer walls on said ejector, steam inlet members carried by certain of said walls for admitting steam between said spaced walls, an axially disposed central tubular umbrella supporting member, a funnel shaped umbrella rib brace supporting member on said tubular supporting member with which the rib braces of an open umbrella may be engaged, said rib brace supporting member being so disposed above the plane of the upper convergent end of said steam ejector for supporting the umbrella cover in spaced relation over said ejector.
